UNITED STATES PATENT OFFICE.

RICHARD G. HARRIS, OF KNOXVILLE, TENNESSEE, ASSIGNOR OF ONE-FOURTH TO
FRANK HAYNES, ONE-FOURTH TO FRANK HAMBRIGHT, AND ONE-FOURTH TO J. T.
LEWIS, ALL OF KNOXVILLE, TENNESSEE.

SAFETY-HEADLIGHT.

1,219,394.

Specification of Letters Patent. Patented Mar. 13, 1917.

Application filed September 15, 1916. Serial No. 120,408.

To all whom it may concern:

Be it known that I, RICHARD G. HARRIS, a citizen of the United States, residing at Knoxville, in the county of Knox and State 5 of Tennessee, have invented new and useful Improvements in Safety-Headlights, of which the following is a specification.

This invention relates to improvements in headlights for use on locomotives, and on 10 street cars.

In carrying out the present invention, it is my purpose to provide a headlight which will be constructed in such manner that the illumination therefrom may be projected 15 laterally as well as forwardly so as to illuminate the roadway at the sides of the vehicle as well as straight ahead, thereby enabling the operator to distinguish objects along the sides of the road and around curves.

20 It is also my purpose to provide a headlight which will embody the desired features of simplicity, efficiency, and durability, and which will embrace comparatively few parts, and be so arranged and correlated as 25 to reduce the possibility of derangement to a minimum.

With the above and other objects in view, the invention consists in the construction, combination, and arrangement of parts 30 hereinafter set forth and falling within the scope of the claims.

In the accompanying drawings:—

Figure 1 is a horizontal section view 35 through a headlight constructed in accordance with the present invention.

Fig. 2 is a front elevation of the headlight.

Referring now to the drawing in detail, 1 designates a casing embodying a bottom wall 40 2, a top wall 3, and back and side walls 4 and 5, respectively, uprising from the bottom wall and connected to the top wall.

The front wall of the casing is indicated at 6, and this wall is bent to form the central front section 7 and side sections 8, arranged at an angle to the front section 7. Each section 7, 8 is formed with an opening, and hinged to one edge wall of the said

opening is a cover plate 9 carrying three bull's-eyes 10, while mounted within the 50 casing in line with the respective bull's-eyes are frusto-conical tubes 11 having their inner ends arranged in adjusted position to one another, while arranged behind the inner ends of the tubes 11 and alining therewith, 55 respectively, are concavo-convex reflectors 12. Suitably secured to the bottom wall of the casing and arranged between the reflectors and the projector tube 11 is a lamp 13, which may be electrically energized or of the 60 oil burning type.

The rear wall 4 of the casing is formed with an opening, and closing such opening is a door 14 whereby access may be had to the interior of the casing. 65

From the foregoing description, taken in connection with the accompanying drawing, it will be seen that I have provided a headlight whereby the light rays from a single 70 burner or lamp may be projected forwardly and laterally from the casing, thereby illuminating the sides of the road as well as that portion of the road straight ahead.

While I have herein shown and described the preferred form of my invention by way 75 of illustration, I wish it to be understood that I do not limit or confine myself to the precise details of construction herein described and delineated, as modification and variation may be made within the scope of 80 the claims and without departing from the spirit of the invention.

I claim:—

1. In a headlight, a casing embodying a bottom wall, a top wall, back and side walls 25 connecting the top and bottom walls, and the front wall formed to provide a front section and angularly disposed side sections, bull's-eyes carried by said sections respectively, projector tubes carried by said casing 30 in line with said bull's-eyes, a lamp at the inner end of said tubes, and reflectors behind said lamps and alining with said tubes, respectively.

2. In a headlight, a casing embodying a 35 bottom wall, a top wall, back and side walls

connecting the top and bottom walls, and the front wall formed to provide a front section and angularly disposed side sections, bull's-eyes carried by said sections, respectively, projector tubes carried by said casing in line with said bull's-eyes, a lamp at the inner end of said tubes, reflectors behind said lamps and alining with said tubes, respectively, and movable plates carried by the side sections and front wall, respectively, 10 and carrying said bull's-eyes.

In testimony whereof I affix my signature.

RICHARD G. HARRIS.
